UNITED STATES PATENT OFFICE.

FRANK O. TAPPAN AND LILLIAN A. EGGLESTON, OF TOLEDO, OHIO.

DESIGN FOR A DRAFTING INSTRUMENT.

SPECIFICATION forming part of Design No. 25,489, dated May 12, 1896.

Application filed April 7, 1896. Serial No. 586,604. Term of patent 14 years.

To all whom it may concern:

Be it known that we, FRANK O. TAPPAN and LILLIAN A. EGGLESTON, of Toledo, in the county of Lucas and State of Ohio, have invented and produced a new and original Design for a Drafting Instrument, of which the following is a full, clear, and exact description.

Reference is to be had to the accompanying drawing, forming a part of this specification which represents in side view a drafting instrument embodying our new design.

The leading feature of the design consists

in the elongated body curved and broadened at one end and having a straight member 15 projecting from the body inward from said curved end and at the side toward which the said end curves.

We claim—

The design for a drafting instrument herein 20 shown and described.
